R. I. GRAF

HOOD FASTENER

Filed Feb. 14, 1927

INVENTOR
Raymond Ivan Graf
BY
Chappel Dean
ATTORNEY

UNITED STATES PATENT OFFICE.

RAYMOND IVAN GRAF, OF GRAND RAPIDS, MICHIGAN, ASSIGNOR TO KEELER BRASS COMPANY, OF GRAND RAPIDS, MICHIGAN.

HOOD FASTENER.

Application filed February 14, 1927. Serial No. 188,031.

The main objects of this invention are:

First, to provide an improved hood fastener or hold down clamp which exerts a downward and likewise a sidewise or lateral pressure to the hood, thereby preventing vibration and rattling.

Second, to provide a hood fastener or hold down clamp having these advantages which is simple and economical in structure, 10 easy to manipulate, and at the same time very efficient for the purpose.

Objects pertaining to details and economies of the invention will definitely appear from the detailed description to follow. The 15 invention is clearly defined and pointed out in the claims.

A structure embodying my improvements is clearly illustrated in the accompanying drawing, in which:

20 Fig. 1 is a detail sectional view of a hold-down clamp embodying the feature of my invention, the same being illustrated in operative relation with a hood fastener.

Fig. 2 is a front elevation partially in 25 section on line 2—2 of Fig. 1.

Fig. 3 is a detail section on line 3—3 of Fig. 1.

Fig. 4 is a fragmentary view partially in 30 section of a slightly modified embodiment or form of my invention.

Fig. 5 is a front elevation of the embodiment shown in Fig. 4.

Referring to the drawing, 1 represents a 35 portion of an automobile hood and 2 an adjacent frame part. These parts are shown conventionally to illustrate the relation of the parts of my improved hood fastener in use.

My improved hood fastener comprises a 40 clamping member consisting of an inner section 3 and an outer tubular section 4, the sections having telescoping engagement.

Housed within the outer tubular section is a spring 5 disposed between the inturned 45 flange 6 at the inner end of the section 4 and a head 7 on the end of the section 3 so that the spring acts to collapse the sections. The section 3 has a head 8 engaged within the slotted coupling member 9 which is attached to a part of the frame of the automobile.

A keeper 10 is mounted on the hood member 1 in position to be engaged by the lever-like latch member 11. This latch member

is pivoted at 12 to the outer end of the 55 clamp member 7.

The inner end of the latch member is provided with a keeper engaging hook 13 and the outer end is formed into a handle or finger piece 14. An arm 15 projects 60 downwardly below the latch engaging hook 13 and carries a resilient rubber abutment 16 adapted to engage the side of the hood.

It will be observed that when the latch member is engaged with the keeper the 65 downward pull of the clamping member spring acts to fulcrum the lever upon the keeper, thereby forcing the lower end of the arm 15 inwardly and forcing the abutment 16 against the side of the hood. An 70 upward lift on the finger piece 14 swings the arm 15 outwardly and the continued lift or pull disengages the latch from the keeper.

In the embodiment shown in Figs. 1, 2 and 3, the latch member is formed as a 75 stamping. In the embodiment shown in Figs. 4 and 5 the latch member is in the form of a casting and has a socket into which the upper end of the clamping member projects. As the parts are the same 80 shape for this manner of forming, and also the matter of proportions, I have employed the same reference numerals on the two embodiments.

My improved hood fastening or hold down 85 clamp is very simple and economical in its parts and the parts are readily assembled. An effective downward and sidewise pressure is exerted to prevent rattling of the hood.

Having thus described my invention what I claim as new and desire to secure by Letters Patent is:

1. The combination in a device of the class described, of adjacent automobile frame and hood members, and a clamp comprising telescoping sections and coacting tension spring acting to collapse the sections, the inner section being pivotally mounted on the frame member, a keeper on said hood member, and a lever-like latch pivotally mounted on the outer section of said clamp and provided with a keeper engaging hook at its inner end, a finger piece at its outer end and a downwardly projecting arm below the keeper 100 engaging hook, said arm being provided with an abutment engaging the side of the hood member whereby the spring acts to exert a 105

downward pull upon the keeper and to force said abutment against the hood member with a lever action, the latch fulcruming about said keeper.

5. 2. An automobile hood clamp comprising a clamp member provided with a tension spring, said clamp member being adapted for attachment to the frame of an automobile, a keeper adapted for attachment to an 10 automobile hood, and a lever-like keeper engaging member recessed to receive and pivotally mounted on the upper end of said clamp member and provided with an outwardly projecting finger piece and an arm 15 projecting downwardly at the side of the clamp member, said arm having a resilient hood engaging abutment.

3. A device of the class described comprising a clamp member adapted for attachment 20 to the frame of an automobile and provided with a tension spring, a keeper adapted for mounting on an automobile hood, and a lever-like latch member pivotally mounted on

said clamp member to coact with said keeper and provided with an outwardly projecting 25 finger piece and an arm projecting downwardly at the side of the clamp member and below said keeper when the latch is engaged with the keeper, said arm having a resilient hood engaging abutment.

4. In a device of the class described, the combination of a spring actuated clamping member, a keeper, and a lever-like latch member pivotally mounted on said clamping member to be engaged with said keeper and 30 provided with an outwardly projecting finger-piece and with an arm adapted to engage the side of the member on which the keeper is mounted when the latch member is engaged with the keeper, the spring actuated 35 clamping member acting on said latch member to fulcrum the same on said keeper and thereby exert pressure through said arm.

In witness whereof I have hereunto set my hand.

RAYMOND IVAN GRAF.
